CLOSURE CAP FOR COLLAPSIBLE OR RIGID TUBES

Theodor F. E. Fuchslocher, Van Nuys, Calif., assignor, by direct and mesne assignments, of twenty-two per cent to Hildegard Moser Behrens, Los Angeles, Calif., twenty-two per cent to Gertrude S. Tenderich, Denver, Colo., and twenty-two per cent to Harry C. Alberts, Chicago, Ill.

Application April 15, 1940, Serial No. 329,657

2 Claims. (Cl. 221—60)

This invention relates to improvements in closures for dispensing tubes and more particularly to closure caps for collapsible tubes of the type generally used to dispense semi-liquid pastes and creams such as tooth paste, shaving cream and cosmetic preparations, although certain features thereof may be used with equal advantage for other purposes.

It contemplates more especially the provision of a simple and inexpensive closure cap structure that is readily assembled in operative position on the discharge necks of standard dispensing tubes for detachable connection therewith and constitutes an improved automatically operating hermetic sealing unit that is similar in external appearance to the known plastic and metallic screw closure caps as to size and dimensions without any appreciable increase in production cost thereover.

Numerous types of automatic closures for collapsible tubes and the like have heretofore been proposed, but these have either been too expensive in construction to warrant their general adoption or were so designed by necessity or otherwise to expose the internal operating elements to the contents which was found highly undesirable from a self-closing operating standpoint. The internal operating members must be simple and comprise few parts that are uninfluenced by the deposit of the contents thereon or between the coacting elements which would impede their normal operation and preclude dependable closing over an extended period of use. To the end of eliminating these undesirable characteristics, the coacting elements must be simple in construction and so arranged as to serve their intended function without being hampered or impaired by contact with the contents.

One object of the present invention is to simplify the construction and improve the operation of devices of the character described.

Another object is to provide an improved automatically operating hermetic sealing closure cap for dispensing tubes of the collapsible or pliable type.

Still another object is to provide an improved hermetic sealing closure cap constituting a self-contained independent unit adaptable for threaded connection to the discharge neck of standard collapsible or pliable dispensing tubes.

A further object is to provide a simple and improved automatic closure unit for dispensing tubes that is responsive to the alternate external

application and relaxation of pressure on the contents of the tube.

A still further object is to provide an improved automatic closure cap comprising relatively few parts of simple construction that facilitates the ready assembly thereof with the tube on a mass production scale.

Still a further object is to provide an improved automatic closure unit for a dispensing tube that is capable of being locked against accidental discharge of the contents during the non-use thereof.

Other objects and advantages will appear from the following description of an illustrative embodiment of the present invention.

In the drawing:

Figure 1 is a plan view of a dispensing tube assembled with a closure cap embodying features of the present invention.

Figure 2 is a side view of the assembled tube and closure cap shown in Figure 1.

Figure 3 is an enlarged sectional view in elevation taken substantially along lines III—III of Figure 1 showing the structural details of the closure cap embodying features of the present invention.

Figure 4 is an enlarged sectional view of the closure cap taken substantially along lines IV—IV of Figure 1.

Figure 5 is a perspective view of the external closure cap body with a part thereof shown in section to clarify the showing.

Figure 6 is a perspective view of the valve forming part of the closure unit.

Figure 7 is a perspective view in elevation of the valve shown in Figure 6.

Figure 8 is a sectional view taken substantially along lines VIII—VIII of Figure 7.

Figure 9 is a perspective view in elevation of the valve actuating spring member for the closure unit.

The structure selected for illustration comprises a closure unit 10 assembled with a cylindrical content dispensing tube 11 of the collapsible or pliable type generally used for dispensing semi-liquid pastes and creams such as tooth paste, shaving cream and cosmetic preparations. The collapsible or pliable tube 11 is made of suitable flexible metal well known in the art having one end 12 closed in the usual manner by crimping with the opposite end 13 terminating in a centrally disposed open discharge neck 14 externally threaded as at 15 to receive the correspondingly internally threaded closure unit 10 as will appear more fully hereinafter.

The tubular discharge neck 14 may be of any size and threads 15 thereon may conform to the type presently used on tooth paste, shaving cream or other popularly used contents marketed in collapsible containers 11. In the present embodiment, the closure unit 10 consists of an internally threaded cylindrical member 16 that is threaded to correspond with and serve as a complement of the external threads 15 on the container neck 14 for engagement therewith. As shown, the internally threaded cylindrical valve member or sleeve 16 has a smooth exterior surface 17 and terminates upwardly in a peripheral shoulder 18 which merges with an upwardly inclined valve surface or seat 19 terminating in a flat circular tip or head 20 positioned axially of the cylindrical sleeve 16 that may be termed a valve member.

In order to permit the passage of the container contents through the valve member 16, a plurality of arcuate openings 21 and 22, in this instance two, are provided in the inclined valve surface or seat 19 and extend to the peripheral shoulder 18. This arrangement of openings 21-22 extends for the major circumference of the valve surface or seat 19 so that the desired volume of contents can be extruded therethrough by subjecting the collapsible container 11 to manual pressure and further rolling the enclosed end 12 in the customary manner to discharge the contents through the tubular neck 14 thereof.

It will be observed that the interior of the inclined valve seat 19 with its flathead 20 is recessed to provide a central concavity 23 to receive the correspondingly shaped conical mid-section 24 of a flat spring 25 terminating in substantially flat and diametrically extending extremities 26-27. When the conical mid-section 24 of the spring 25 rotates in the conical cavity 23 of valve member 16, the substantially flat extremities 26-27 thereof protrude through oppositely inclined slots 28 and 29 provided in diametrically opposite sides of the cylindrical valve member 16. It is to be noted that the oppositely inclined slots 28 and 29 are disposed equi-distant of the arcuate content passage openings or apertures 21-22 and these provide oppositely curved camming edges 30 and 31 that cooperate with the flat spring extremities 26-27 to permit relative rotation with a cap member 32 having an inner cylindrical wall 33 having a diameter corresponding with the exterior diameter of the valve member 16 for relative rotation therebetween and to provide a close fitting enclosure therefor.

As shown, the cap member 32 has an exteriorly knurled annular peripheral shoulder 34 to enable the manual finger grasp thereof for imparting convenient rotation thereto as will appear more fully hereinafter. The inner wall 33 extends upwardly for a distance commensurate with the exterior smooth cylindrical wall 17 of the valve member 16 so as to constitute a complement thereof. To this end, the inner top surface 35 of the cap 32 is provided with an upwardly inclined conical seat 36 corresponding to and serving as a complement of the valve seat 19 so as to present close fitting contacting surfaces to close the content passage openings 21-22 when the valve member 16 and the cap member 32 are in engaging contact between their smooth conical seats 19-36. The conical seat 36 in the cap member 32 terminates in a circular opening 37 that extends axially therethrough to receive the correspondingly shaped tip 20 of the

valve member 16 to serve as a tight fitting closure therefor in conjunction with the conical surfaces 19-36 which merge downwardly therefrom.

In order to retain the valve member 16 and the cap member 32 in assembled relation through the medium of the flat spring 25, the interior cylindrical wall 33 of the cap member 32 is provided with diametrically opposed recesses 38 and 39 that are shaped to receive the flat extremities 26-27 of the spring member 25. The spring member 25 must be inwardly flexed to contract the conical mid-section 24 thereof to enable the spring extremities 26-27 to be lodged in the recesses 38-39, thereby retaining the valve 16 and the cap member 32 in assembled relation. As a result, the mid-section 24 normally imparts a downward urge to the extremities 26-27 so that the cap member 32 tends to engage the valve tip 20 so that the inclined and complementary valve seat surfaces 19-36 will be normally in engaging contact to close the openings 21-22 in the valve member 16 and the axial opening 37 in the top of the cap member 32.

It will be apparent, therefore, that the projecting extremities 26-27 of the flat spring 25 will ride the opposite inclined camming edges 30-31 of the openings 28-29 in the valve member 16 and serve to permit relative rotation thereof with the valve cap 32 so that the complementary closure members 16-32 will normally be in contacting engagement to serve as an automatic closure for the discharge orifice in the neck 14 of the container 11. With the position occupied by the flat spring 25, it normally is disposed beneath the valve tip 20 between the content passage openings 21-22 in the valve seat 19, the spring 25 being in flat contact with the inner surface therebetween so that its operating characteristics are not impaired by an undesirable exposure to the contents in passing through the openings 21-22 and out of the cap opening 37.

Consequently, the working parts are not "frozen" by the contents of the container 11 after the extended use of the closure members 16-32 while the contents is discharged in increments over interrupted intervals of time. It will be observed, therefore, that when the contents of the container 11 is expelled in increments by external pressure on the walls of the container 11 and by rolling its closed edge 12, the contents will tend to pass through the arcuate openings 21-22 and abut against valve seat surface 36 of the cap member 32, thereby tending to elevate the latter together with the entire body member 32 from its valve seat 19 to provide a passage therebetween (Figure 3).

This separating displacement between the complementary valve member 16 and cap member 32 is afforded or permitted by the diametrically opposite slots 28-29 that are wider than the thickness of the flat spring extremities 26-27 to permit this relative displacement therebetween. When the pressure on the container 11 has been released and relaxed, the flat spring 25 will return the complementary valve member 16 and cap member 32 to its initial position with contacting engagement re-established between the valve seats 19-36, thereby closing the passage openings 21-22 and the central discharge opening 37.

So that accidental pressure on the walls of container 11 will not accidentally extrude the contents while the container 11 is being carried in a suit-case or otherwise packed for shipment, locking against any permitted separation between

the valve member 16 and cap member 32 is effected by merely rotating the latter in a clockwise direction (viewed from Figure 2) relative to the valve member 16. This relative rotary displacement is effected with a fractional turn and serves to bring the valve seat 19 tightly against the valve seat 36 in tight frictional engagement owing to the fact that the projecting extremities 26-27 of the flat spring 25 ride against the cam edges 30-31 to bring the cap member 32 down against the valve member 16 in an extreme position.

In this extreme position, the camming edges 30-31 of the slots 28-29 in the valve member 16 assume a position in the cap member recesses 38-39 adjacent the inner top wall 35 thereof to preclude any further relative reciprocal movement between the complementary members 16-32. As a result, there cannot be any separation between the valve seats 19-36 by any further external application of pressure on the container 11. To further permit the separation of the valve engaging surfaces 19-36 when desired to continue the normal use of the container 11 for the discharge of the contents therefrom, all that is necessary is to turn the cap member 32 in a counterclockwise direction (viewed from Figure 2) so as to return the parts to their initial position and provide for relative displacement therebetween within the limits controlled by the width of the recesses 38-39 relative to the thickness of the spring extremities 26-27.

It will be apparent from the foregoing description that a comparatively simple, dependable and inexpensive closure cap construction of the automatic closing type has been provided with a minimum number of parts and without the normal impairment created by the exposure thereof to the contents of the container 11 as such are discharged therefrom. The locking feature described supra is also of importance and eliminates the undesirable possibility of leakage when the container 11 is not in use and pressure is accidentally applied externally thereto.

Various changes may be made in the embodiment of the invention herein specifically described without departing from or sacrificing any of the advantages of the invention or any of the features thereof, and nothing herein shall be construed as limitations of the invention, its concept or structural embodiment as to the whole or any part thereof, except as defined in the appended claims.

I claim:

1. In a device of the character described, the 55

combination with a receptacle having a tubular neck serving as a discharge orifice, of a pair of complementary closure members associated with said neck to normally close the discharge orifice, 5 one of said closure members having an extended valve head with a conical recess thereunder, the other of said members comprising a cap having an annular valve seat to receive said valve head for complementary fitted engagement therebetween, and a flat spring bar for rotatively and reciprocally connecting said closure members, said flat spring bar having a conically tapered mid-section and straight end sections for continuous contact against said valve head and its conical recess for the entire diametrical extent thereof to normally urge one of said members in closing contact with the other of said members and to permit their relative separating movement for the discharge of the receptacle contents under pressure.

2. In a device of the character described, the combination with a receptacle having an externally threaded tubular neck serving as a discharge orifice, of a pair of complementary closure members threadedly engaged with said neck to normally close the discharge orifice, one of said closure members having a centrally disposed extended valve head with a conical recess thereunder, the other of said members comprising a cap having an annular valve seat in axial alignment with said discharge orifice to receive said valve head for complementary fitted engagement therebetween, and a flat spring bar for rotatively and reciprocally connecting said closure members, said flat spring bar having a conically tapered mid-section and straight end sections for continuous contact against said valve head and its conical recess for the entire diametrical extent thereof to normally urge one of said members in closing contact with the other of said members and to permit their relative separating movement for the discharge of the receptacle contents under pressure, there being a pair of diametrically opposed internal recesses in the 30 wall of said cap member and a pair of aligned apertures in the wall of said valve member to receive said flat spring means for maintaining said members in assembled relation, each of said aligned apertures having oppositely inclined camming edges with narrow and wide ends for cooperation with said flat spring member to enable their relative reciprocation and effect locking engagement between said closure members responsive to relative rotation therebetween.

THEODOR F. E. FUCHSLOCHER.
